(57) **CLAIM**

The ornamental design for a ceiling hoop, as shown and described.

DESCRIPTION

This application is related to co-pending U.S. patent application Ser. No. 12/098,330, filed on even date herewith, entitled Rack Accessories, the entire contents of which are incorporated herein by reference.

FIG. 1 is an isometric view of a ceiling hoop;

FIG. 2 is a front view thereof;

FIG. 3 is a right end view thereof, a left end view being a mirror image of the right end view;

FIG. 4 is a top view thereof; and

FIG. 5 is a bottom view thereof; and,

FIG. 6 is an additional isometric view of a ceiling hoop having a shorter hanging assembly.

The broken lines shown are included for the purpose of illustrating environmental structures and form no part of the claimed design.

1 Claim, 6 Drawing Sheets

FIG. 4

FIG. 5

FIG. 6
